UNITED STATES PATENT OFFICE.

FREDERICK R. ROBERTS, JR., OF CONCORD, NEW HAMPSHIRE, ASSIGNOR TO WM. B. DURGIN COMPANY, OF CONCORD, NEW HAMPSHIRE, A CORPORATION OF NEW HAMPSHIRE.

DESIGN FOR A VASE OR SIMILAR ARTICLE.

46,751.

Specification for Design.

Patented Dec. 8, 1914.

Application filed September 21, 1914. Serial No. 862,811. Term of patent 7 years.

To all whom it may concern:

Be it known that I, FREDERICK R. ROBERTS, Jr., a citizen of the United States, residing at Concord, in the county of Merrimack and State of New Hampshire, have invented a new, original, and ornamental Design for Vases or Similar Articles, of which the following is a specification, reference being had to the accompanying drawings.

Figure 1 is a front view of the vase, showing my design. Fig. 2 is a side elevation with the base or bottom broken away.

I claim—

The ornamental design for a vase or similar article, as shown.

FREDERICK R. ROBERTS, JR.
